UNITED STATES PATENT OFFICE

ETTA M. SQUIRES, OF AMITYVILLE, NEW YORK

DESIGN FOR A WALL PLATE FOR ELECTRIC BUTTONS

Application filed October 31, 1929. Serial No. 33,231. Term of patent 3½ years.

To all whom it may concern:

Be it known that I, ETTA M. SQUIRES, a citizen of the United States, and a resident of Amityville, in the county of Suffolk and State of New York, have invented the new, original, and ornamental Design for Wall Plates for Electric Buttons, of which the following is a specification.

Reference is had to the accompanying drawing, forming part thereof, wherein

Figure 1 is a plan view of a wall plate for electric buttons showing my new design;

Figure 2 is a sectional view through Figure 1 on the line 2—2.

I claim:

The ornamental design for a wall plate for electric buttons substantially as shown.

ETTA M. SQUIRES.
